ABSTRACT OF THE DISCLOSURE

Device for obtaining earth samples comprises an inner tube having cutting means at its forward end and adapted to be driven into the earth, fingers within the tube for detaching a core therewithin when the tube is pulled up, an outer casing frangibly attached to the inner tube, passageways between the tube and casing for receiving water and, in a preferred embodiment, valve means for controlling the admission of water to said passageways adapted to be closed when said tube is withdrawn from the earth and broken loose from said outer casing.

This is a continuation-in-part of application Ser. No. 887,657, filed Dec. 29, 1969.

SUMMARY OF THE INVENTION

This invention relates to apparatus for use in obtaining samples from the earth, particularly the sea bed.

The invention has for its object the provision of improved apparatus for this purpose.

It is one of the principal objects of this invention to provide a sampler device which is adapted to be driven into the sea bed by means which impart it to a high initial speed, and which can then readily be withdrawn from the sea bed, bringing with it the required sample.

A further object of the invention is the provision of such a sampler device which can easily be withdrawn from the sea bed even if it has been driven into the latter to a substantial depth.

According to the invention a sampling device is provided which is adapted to be fixed into the earth to take a sample therefrom, wherein the device comprises a tube having a cutting part at its forward end, guide-fins towards its other end and separating fingers towards its forward end for separating a sample within the tube when a rearward pull is applied to the latter, wherein the tube is surrounded by a jacket which is initially attached to it but which is adapted to be left behind in the cavity left in the earth when the tube containing the sample is withdrawn, the jacket then providing a lining for the cavity and facilitating the retraction of the tube with its sample.

A first form of device for taking samples from the earth when it is projected into the latter is constituted by a cylindrical tube which is provided at its forward portion with a cutting element or part which is provided internally with separating fingers actuatable by a pull applied to the sampling tube, the said tube being equipped with guide-fins and being surrounded by a connecting jacket, said jacket being adapted to be left in position in the cavity left when the sample is removed by pulling on the device, the said jacket also providing a lining for the cavity and facilitating withdrawal of the tube with a sample in it by a pull applied to the tube.

In this embodiment, water is allowed to circulate between the outer wall of the main tube and the jacket surrounding it, so as to ensure the filling of the cavity formed when the plug-sample is removed under the effect of the pull applied to the sampling tube.

2

While such devices are perfectly suitable for the collection of consolidated samples, their use is unsatisfactory when collecting unconsolidated samples, because the sea water washes the core sample away during the raising of the sampler.

In certain slow-percussion samplers, there already exist pistons which shift during sampling and block off the top of the sampler, thus protecting the sample from being washed away. However, such samplers cannot be operated quickly, because the penetrating impact is caused by the dropping of metal weights.

Fast-percussion samplers cannot be fitted with such pistons, which would have the effect of immobilizing them before they come into contact with the sea bed.

The present invention provides a method of removing this drawback, by shutting off the underwater percussion sampler when it has completed its downward movement, without the use of a piston.

For this purpose, the water-circulation passages are fitted with one or more mobile shut-off valves, of an elastomer material, for instance.

According to one embodiment of the invention, the valves, in the open position, are secured by means of one end of a component which pivots around a fixed point, the other end being connected to a bolt on the casing.

According to another embodiment of the invention, the releasing and closing of the valves are controlled by the outer casing sliding along the sampler member.

According to yet another embodiment of the invention, the sliding of the outer casing along the sampler member is caused by the pull exerted on the sampler to withdraw it from the sea bed.

The sampler according to the present invention may also contain a water intake in the releasable outer casing, near the top of the said casing.

The invention will be better understood from the following description of two embodiments thereof, taken in conjunction with the accompanying drawings.

In the drawings:

FIG. 1 is a side view of a first embodiment of the invention, partly broken-away, and partly as a longitudinal section taken through the sampler device;

FIG. 2 is a partial transverse cross-section through one-half of the device shown in FIG. 1; and

FIG. 3 is an axial cross-sectional view illustrating an embodiment comprising a shut-off device.

The sampler device shown in FIG. 1 comprises a main tube 1 which is connected by means of screw-threads to a body 2, this connection being at the upper part of the tube 1.

At its lower part the main tube 1 carries a cutting element 3. This cutting element has a tapered profile to enable it to penetrate into the sea bed without too much resistance. The tube 1, the outer part of which is formed with ribs and channels (see FIG. 2), is surrounded by a jacket 4 in such manner that there is unoccupied space between the outer part of the tube 1 and the inner surface of the jacket 4.

At its lower part the main tube 1 carries a sleeve 6 which supports an inner jacket 5, which might extend along the entire length of the device. The purpose of this sleeve 5, which is connected to the body 2, is to accommodate the sample taken from the sea bed. At the bottom of the sleeve 5 the sleeve 6 carries steel wires 7, which form a "spider" and which are intended to keep the plug-like sample in position once it has been obtained. The sleeve 6 also carries at its lower end an arrangement of

separating fingers 8, which rock about spindles carried

by the sampling device and which cut into the ground when a pull is applied to the device to withdraw it.

The forward or lower portion 9 of the jacket 4 is arranged to form a continuation of the cutting element 3. Passages 10 and 11 enable sea water to circulate between the tube 1 and the jacket 4 to fill the space 12, which is left when the plug sample is retracted. When the device is driven forward, the outer jacket 4 is locked to the assembly by means of a stop 13.

The device also comprises guide fins 14 which have holes 15 for attaching the device to the firing system. The numeral 16 indicates passages in the body 2 which enable water to be delivered to the passages 11 and 12 and to the space 17 between the main tube 1 and the jacket 4. The numeral 18 indicates shear-pins which temporarily attach the jacket 4 to the rest of the device. These shear-pins could be replaced by check screws. Their function will be explained later.

Finally, a centering element 19 enables the assembly to be fitted and aligned as a whole in the firing system.

In FIG. 2, the numeral 1 indicates the main tube, the outer portion of which is formed with ribs and channels. The numeral 4 indicates the outer jacket. The numeral 20 indicates the ribs, while the spaces between the main tube 1 and the outer jacket 4 provided by the channels are shown at 17.

This sampling device operates as follows:

The assembly is placed in a firing gun, and when it is in position, the explosive that drives the device towards the sea bed is detonated. To be most effective, the apparatus should preferably be positioned approximately two metres from the sea bed so that the sampling device, before touching the sea bed, will have reached an initial high speed. The sampling device is braked to only a slight extent during its travel, as a result largely of the form of the passages 16, which are substantially an extension of the sample-carrying tube and which have a total cross-section greater than that of the tube. The water can thus circulate more freely and the braking action is slight.

When the sampling device enters the sea bed, the head 3 enables it to bury itself in the manner of a driven stake, and the sample fills the interior of the device, the outer jacket 4 exercising a rubbing action as it slides into the sea bed.

The sampling device becomes deeply buried in the sea bed and is then braked by the fins 14 which have also acted as guiding and stabilizing means for the device. Once penetration has been effected, a pull is applied to the sampling device with the help of cables previously passed through the holes 15. Under the combined effect of this pull and friction of the sea bed, the pins 18, or the check screws which can replace them, disengage the jacket 4, which then remains in the cavity formed by the tubular construction of the device. The fingers 8 rock and part off the plug-like sample in the jacket 5, and the mobile "spider" 7 or wires retains the plug in the jacket 5.

Also, water can circulate freely by way of the passages 16, 11 and 10, and can take the place of the plug-like sample. Retraction can then be carried out without great effort and a pull of a few tons usually suffices to disengage the sampling device from the sea bed.

For the purpose of recovering the sample, the body 2 is removed and the tube 5 can then be readily disengaged so that a suitable representative sample of the sea bed can be obtained in a simple manner.

In FIG. 3, the left half of the figure is a cross-section taken through one-half of the upper part of a percussion sampler equipped with a shut-off system controlled by the sliding of the releasable outer casing with the shut-off system in the open position, occupied during the descent of the sampler and its penetration into the sea bed, while the right half is an axial cross-sectional view showing the same system in its closed position, occupied during withdrawal of the sampler, with reference numerals 1', 2', etc. corresponding to 1, 2, etc. on the left-hand side.

The main component of the sampler 1 is screwed on to the body 2 forming the head of the sampler, and which receives the percussion impact at 19, from a propelling device, not shown. Two passages 16 allow the column of water occupying the sampler tube 5 to be emptied out at the moment of percussion, hindering the sampling operation as little as possible. The sliding casing 4, which remains attached to the sides of the hole when the sampler is raised to the surface after sampling, and which makes its extraction from the sea bed easier, is fixed to the coupling 2 by shear screws 18.

The shut-off valve, shown in the left-hand part of the figure in the open position, consisting of a plug 21, of an elastomer material, for instance, fixed on an axis 30 to a seesaw lever 23 which rotates round a fixed point 22, and the other end of which 24 is held, in the open position, by a bolt 25; this bolt slides in guides 26, and is connected at 27 to the releasable sliding casing 4. A drawback spring 28 forces the plug 21 on to the seat 29 of the passage 16 as soon as the bolt 25 is drawn downwards by the casing 4. To ensure hermetic shutting-off of the passages, each plug 21 has a slight degree of play on its axis 30, so that it can fit itself into the passage. Cables such as 31 allow the sampler to be withdrawn. There is also a water intake 32, letting water flow between the outer casing 4 and the sampler 1, and allowing it to be removed without disturbing the sampler.

The device operates as follows.

When the sampler penetrates into the sea bed, the shut-off valve is in the open position shown at 21. As soon as penetration is completed, the sampler is pulled up by the cables 31, to withdraw it. Under the combined effect of this pull and the friction from the sea bed, the screws 18 snap, freeing the casing 4, which remains attached to the sides of the hole. The bolt 25, which is fixed to the casing 4, slides downwards through the slides 26, to the position 25'. The lever 23 is thereupon freed, and the drawback spring forces it into the position 23', so that the plug 21 comes against the seat 29 of the passage 16, blocking it off. With the passage blocked, water no longer circulates inside the casing 5 of the sampler, preventing the soil sample from being washed away by seawater throughout the raising of the sampler.

In another embodiment of the invention, not illustrated, the bolts 25, instead of being moved by the casing 4 sliding along the sampler 1, following the pulling of the sampler by the cables 31 in order to raise it to the surface, may be moved directly as the result of such pulling, by means of a simple lever which operates as soon as an upward pull is actually exerted on the cables 31.

What is claimed is:

1. A sampling device adapted to be driven into the earth to take a sample therefrom, in which said device comprises a tube having cutting means at its forward end, external guide fins toward its other end, and internal separating fingers toward its forward end for separating a sample within the tube when a rearward pull is applied to said tube, a jacket encircling said tube, means frangibly attaching said jacket to said tube, whereby said jacket may be separated from said tube and left behind in the earth when the tube containing the sample is withdrawn, and passages permitting water to flow into and out of said tube.

2. A sampling device as claimed in claim 1 in which the tube is cylindrical with longitudinal ribs and channels formed in its outer surface.

3. A sampling device as claimed in claim 1 comprising valve means which controls the entry of water into said passages, and stop means mounted on said tube which holds said valve means in open position as long as said tube remains attached to said jacket.

4. A sampling device as claimed in claim 3 comprising spring means mounted to bias said valve means toward a closed position, said stop means being mounted to release said spring when said tube and jacket are separated.

3,716,107

5

5. A sampling device as claimed in claim 3 comprising a simple lever mounted to close said valve means when said tube is separated from said jacket.
